STOCKING FOOT

Guenther Kasket, New York, N. Y.

Application August 12, 1942, Serial No. 454,492

6 Claims. (Cl. 36—10)

My invention relates to improvements in articles of footwear, and, more particularly, to stocking feet ending at or below the ankle of the wearer's foot.

Such stocking feet may be worn underneath or over ordinary stockings or socks, or without stockings, depending upon the purpose. For instance, a stocking foot may be used when applying a medication for holding the latter in place, or for protecting a stocking proper from being affected thereby. A stocking foot may also serve for reducing the wear of an ordinary stocking. A stocking foot may also be favorable as an additional lining or filling when wearing sport shoes, ski shoes and the like. Lastly, such stocking feet are worn for reasons of fashion, especially for providing more comfort when wearing shoes without visible socks or stockings.

One of the drawbacks of the customary stocking feet is their tendency to come out of place either by sagging down into the shoe or by creeping out of it, causing discomfort or disorderly appearance. It has been suggested to provide the opening of stocking feet with a hem containing an elastic band or to line the heel portion with relatively rigid material in order to prevent the stocking heel from creeping upwardly and out of the shoe. Both means are imperfect as regards comfort and appearance.

It is an object of my invention, in one of its aspects, to improve stocking feet for the above-mentioned purposes so as to eliminate discomfort due to localized elastic or rigid pressure while providing a snug fit and a tendency of the article to stay in proper place on the wearer's foot.

Another object of the invention is to provide new cuts for blanks which are easy to fabricate and at the same time to ensure a very snug and even fit over at least the entire heel, tendon and arch portion of the wearer's foot.

A further object of the invention is the provision of stocking feet applicable and especially designed for open-heel shoes, sandals and the like footwear. The known stocking feet cannot well be worn with shoes of these types because the heel and middle portions of the stocking feet would be visible through the openings and interstices of these shoe constructions.

An object is also to simplify the stocking feet to be worn in cases where the protection of the toe portion of ordinary stockings or the application of medications to the toes or balls is the main purpose.

The invention will be understood from the

embodiments described hereinafter in connection with the drawing in which—

Fig. 1 is a perspective view of a stocking foot embodying features of the invention;

5 Figs. 2 and 3 are representations of two blanks, shown in developed form, used in fabricating a stocking foot such as shown in Fig. 1;

Fig. 4 is a view of the stocking foot of Fig. 1, folded flat upon a table and showing the relative position of the two blanks of Figs. 2 and 3 properly joined together;

Fig. 5 is a side view of another embodiment, shown folded flat;

Fig. 6 illustrates the same article, opened up, and in a perspective view; and

10 Fig. 7 is a perspective view of a further embodiment.

Referring to Figs. 1, 2, 3 and 4, the stocking foot here illustrated is composed of two blanks 20 1 and 2. Blank 1 has a substantially arcuate shape, the two half-portions of the arc being symmetrical to the line A—B and forming an inwardly projecting point at A. The blank 2 has one long edge 21 of substantially straight 25 shape and two adjoining short edges 22 and 23 extending at substantially right angles to the long edge 21. The remaining edge 24 forms a curved line pointed at C towards the long straight edge 21.

30 The two blanks are cut from textile or the like material such as woven or preferably knit material. The blank 2, destined to form the heel portion of the stocking foot, consists of a material with different degrees of stretch in different 35 directions. I prefer using knit material which has greatest stretch in one direction and is relatively unyielding at right angles thereto. For purposes of illustration, areas 16 have been depicted as knitted areas in blank 1, and areas 40 17 have been indicated as knitted areas in blank 2. The material is so arranged when cutting the blank 2 that the greatest stretch extends 45 in the direction of the arrow 25. The blank 1, forming the toe and ball portion of the stocking foot, consists preferably of the same material. However, the cut is so directed that the greatest stretch of blank 1 extends substantially as indicated by the arrow 15, i. e. at right angles to the stretch of the heel blank 2. This is further 50 demonstrated by the fact that the wavy lines of areas 16 are transversely disposed to the wavy lines of areas 17 in Figs. 1 and 2.

When assembling the two blanks, blank 1 is folded along the line A—B so as to form a crease between those points. Now, the two half-arcs

lie flat on one another, with the outer peripheral edges 11 and 12 in registry with each other, as the inner peripheral edges 13 and 14 are in registry with each other. Consequently, end points D and F are in registry with each other, as are end points E and G, as is apparent from Fig. 4. Then, the edges 11 and 12 are joined together, preferably by sewing, along the entire arcuate portion of the outer periphery so as to form a seam extending from point A to points E and G. This seam is 10 denoted by 3 in Fig. 1.

The next step of manufacture is to attach blank 2 to blank 1 so that the long edge 21 joins the ends 26 and 27 of blank 1 as indicated in Fig. 4. As a result, the short edges 22 and 23 form a continuation of the edges 13 and 14, respectively, of the blank 1. Finally, the two portions of the curved edge 24 are joined together so as to form a seam extending from point C upwardly to the registering points H and I. The latter seam appears in Fig. 1 at 4. Seams 3 and 4 extend in the longitudinal and axial directions of the finished article, while the seam resulting from the joining together of the two blanks extends transversely as is apparent in Fig. 1 at 5. The sequence of the folding and joining operations can, of course, be varied without affecting the result. Likewise, the heel blank 2, if cut in the then proper direction relative to the stretch of the material, may also be arranged so that the long edge 21 forms the continuation of the lines 13 and 14 while the short edges 22 and 23 abut against the ends D—E and F—G, respectively, of blank 1.

The finished stocking foot has the following properties. The heel portion is elastic in the horizontal or longitudinal direction of the foot of the wearer, but virtually unstretchable in the vertical direction, as appears from the wavy lines of stretch of area 17. The front portion of the article, however, is inherently elastic in the vertical direction, as appears from the wavy lines of stretch of areas 16. Owing to the horizontal pull acting in the heel portion when worn, the latter is tightly held against the wearer's foot, but its vertical inelasticity prevents it from creeping vertically. As a result, the stocking foot is elastically held in place merely by the inherent differences in stretchability of the material. This suffices, as a rule, to obtain the desired advantages without requiring additional holding means, although such means may also be employed additionally if, for instance, special requirements are to be met.

For instance, the rim of the stocking foot may be reinforced by hemstitching, bias tape or an elastic band, or a reinforcing lining may be arranged at the upper end of the heel portion as is indicated at 6 in Fig. 1. Such a lining, however, may be smaller and lower than heretofore customary, as it need not contribute to holding the article in place and should not interfere with the effect of the vertically elastic heel portion.

When providing the stocking shoe with an elastic rim portion, advantage can be taken of another feature of my invention also embodied in the example illustrated in Fig. 1. According to this illustration, the upper rim of the foot opening, at least along the edges 13 and 14 (see Figs. 1 and 2), is formed by a downwardly extending peripheral zone 7 of increased horizontal elasticity (elongation) in order to obtain a snug fit over the entire arch and tendon area of the article. This increased elongation can be obtained by corresponding knitting methods, for instance. It is preferable, however, to provide the material

with elastic threads or strands, such as rubber bands, which surround the foot opening partially or wholly, each extending substantially in a horizontal direction when in proper wearing position. The strands are so imbedded or otherwise integrated with the material and cover a relatively extensive area that they are not visible as such and cannot cause localized pressure or warping of the material. The strands lying closer to the opening are shorter than those farther away so that the article tends to adapt itself closely and evenly to the foot of the wearer without exerting localized pressure at any point of the area.

The last-mentioned feature of my invention contributes to improving the horizontal pull on the vertically elastic heel portion of the stocking foot. It will be understood, however, that even without this feature a stocking foot as described above is ordinarily sufficient to ensure good wearing qualities, and in this respect is superior to the known articles of this type. On the other hand, the use of an elastic area of downwardly increasing length or diameter, as described in the foregoing, may also be applied with advantage to other constructions of stocking feet. This will be apparent from Figs. 5 to 7 of the drawing.

The stocking foot shown in Figs. 5 and 6 covers the toe and ball portion of the wearer's foot while leaving the heel portion and part of the middle portion open. The article can be formed of a single blank, having a bag-like front portion 8 and a strap-like rear portion 9. The strap 9 serves merely to hold the toe portion in place and is covered by the shoe structure when worn. An elastic area 10 is provided in accordance with the description given in connection with Figs. 1 and 2. Another elastic area 10' extends around the lower rim of the article.

Articles according to Figs. 5 and 6 are advantageous when the main purpose is to protect the most affected parts, i. e., the toe portion, of an ordinary stocking, or when wearing no stockings and heelless shoes or sandals.

Fig. 7 represents the use of an elastic area 31 as set forth above in connection with a stocking foot 30 of any suitable construction, for instance a one-blank or circular-knit article. The zone 31 contains a multiplicity of elastic strands surrounding the foot opening, each outer strand, in the worn state as well as relaxed, having greater length than the adjacent inner one, so that the shape of the elastic arch and tendon area follows closely the shape of the corresponding area of the wearer's foot.

I claim:

1. A separate and distinct manufacture, consisting of a stocking foot, the stocking foot comprising a section for encasing the toes and the foot rearwardly therefrom to substantially the ball of the foot, and means for engagement around the foot at the heel but well above the sole of the foot, the engagement means and the section cooperating to provide an opening for insertion of the foot into said section and an opening for projection of the heel of the foot below said engagement means, said section and engagement means having lines of greater elasticity in zones immediately adjacent the edges of the openings than in zones removed from said edges.

2. A separate and distinct manufacture, consisting of a stocking foot, the stocking foot comprising a section for encasing the toes and the foot rearwardly therefrom to substantially the ball of the foot, and means integral with said sec-

tion for engagement around the foot at the heel but well above the sole of the foot, the engagement means and the section co-operating to provide an opening for insertion of the foot into said section and an opening for projection of the heel of the foot below said engagement means, said section and engagement means having lines of greater elasticity in zones immediately adjacent the edges of the openings than in zones removed from said edges.

3. A separate and distinct manufacture, consisting of a stocking foot, the stocking foot comprising a section for encasing the toes and the foot rearwardly therefrom to substantially the ball of the foot, and means for engagement around the foot at the heel but well above the sole of the foot, the engagement means and the section co-operating to provide an opening for insertion of the foot into said section and an opening for projection of the heel of the foot below said engagement means, the section and the engagement means being formed of a single piece of material, said section and engagement means having lines of greater elasticity in zones immediately adjacent the edges of the openings than in zones removed from said edges.

4. A separate and distinct manufacture, consisting of a stocking foot, the stocking foot comprising a section for encasing the toes and the foot rearwardly therefrom to substantially the ball of the foot, and means for engagement around the back of the foot only between the heel and the ankle, the engagement means and the

section co-operating to provide an opening for insertion of the foot into said section, said section and engagement means having lines of greater elasticity in zones immediately adjacent the edges of the opening than in zones removed from said edges.

5. A separate and distinct manufacture, consisting of a stocking foot, the stocking foot comprising a section for encasing the toes and the foot rearwardly therefrom, and means for engagement around the back of the foot only between the heel and the ankle, the engagement means and the section co-operating to provide an opening for insertion of the foot into said section, said section and engagement means having lines of greater elasticity in zones immediately adjacent the edges of the opening than in zones removed from said edges.

10 6. A separate and distinct manufacture, consisting of a stocking foot, the stocking foot comprising a section for encasing the toes and the foot rearwardly therefrom to substantially the ball of the foot, and means for engagement around the back of the foot between the heel and the ankle, the engagement means and the section co-operating to provide an opening for insertion of the foot into said section, said section and engagement means having lines of greater elasticity in zones immediately adjacent the edges of the opening than in zones removed from said edges, the lines of elasticity being greater in length at a greater distance from the edges.
